INVENTOR

Edward P. Beach,

BY ~~drawn &~~ ATTY'S.

UNITED STATES PATENT OFFICE.

EDWARD P. BEACH, OF NEWARK, NEW JERSEY, ASSIGNOR TO UNGER BROTHERS, OF SAME PLACE.

DESIGN FOR A SLEEVE-BUTTON, &c.

SPECIFICATION forming part of Design No. 19,728, dated April 1, 1890.

Application filed December 10, 1889. Serial No. 333,287. Term of patent 3½ years.

To all whom it may concern:

Be it known that I, EDWARD P. BEACH, a citizen of the United States, residing at Newark, in the county of Essex and State of New Jersey, have invented and produced a new and original Design for Sleeve-Buttons and other Similar Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 represents a face or plan view of my design for a sleeve-button and other similar articles, and Fig. 2 is a side or edge view of the same, similar letters of reference indicating corresponding parts where they occur.

These two views are deemed sufficient to fully illustrate my design, the leading feature of which consists in the peculiar configuration presented in the surface or face of the sleeve-button or other article, as will be hereinafter set forth and claimed.

Referring to said drawings, *b* and *c* indicate

two wire-like structures or parts formed into or presenting a series of convolutions and curvatures intersecting and intertwining with one another in a peculiar manner or form, the part *c* presenting the appearance of a heavy line forming a series of arcs of a circle at the outer edge of the design, which intersect with and cross one another, terminating in a series of curvatures of an ovate form at the central portion of the design, and the part *b* presenting in a smaller line than *c* a series of rings encircling said arcs and connected by lines *a*, which pass through the said figures of an ovate form, a space being left open at the center for the reception of a gem or other ornament, if desired, as will be seen and understood upon reference to Fig. 1.

What I claim is—

The design for a sleeve-button or other similar article herein shown and described.

In testimony that I claim the foregoing I have hereunto set my hand this 4th day of December, 1889.

EDWARD P. BEACH.
